UNITED STATES PATENT OFFICE.

DENNIS E. CROWLEY, OF MILWAUKEE, WISCONSIN.

RAIL-ANCHORING DEVICE.

1,213,338.

Specification of Letters Patent. Patented Jan. 23, 1917.

Application filed April 15, 1916. Serial No. 91,297.

To all whom it may concern:

Be it known that I, DENNIS E. CROWLEY, a citizen of the United States, and resident of Milwaukee, in the county of Milwaukee, and State of Wisconsin, have invented certain new and useful Improvements in Rail-Anchoring Devices; and I do hereby declare that the following is a full, clear, and exact description thereof.

The present invention relates to new and useful improvements in rail anchoring devices, more particularly of that type including a rail bed plate, and means whereby insertion of securing spikes into the bed plate procures a clamping action on the rail to anchor the same.

It is in general the object of the present invention to simplify the structure and improve the efficiency of devices of this character, and the convenience with which such devices can be assembled.

It is more specifically an object to provide a rail anchoring device whereby the rail gripping means bears laterally against the body of the bed plate to thus provide a structure of maximum strength.

With the above and other objects and advantages in view, the invention resides more particularly in the novel combination, arrangement and formation of parts more particularly hereinafter described and more particularly pointed out in the appended claim.

In the drawings: Figure 1 is a top plan view of my improved rail anchoring device associated with a rail, the ball portion of the rail being broken away, and portions of the anchoring device being in section. Fig. 2 is a vertical sectional view through the anchoring device on the line 2—2 of Fig. 1.

Referring now more particularly to the accompanying drawings, 5 designates a rail bed plate which is seated on the tie 6 and the top face of this plate is provided with a transverse recess 7 receiving the base flange portion of the rail 8 whereby the side edges of the base flange portion abut against the shoulders formed by the sides of the recess. At diagonally opposed portions the bed plate is provided with vertical passages 9 having their inner side portions extended inwardly of the sides of the recess whereby they underlie the edge portions of a rail disposed in the recess and these passages are for the reception of rail spikes 10. The upper portions of the outer sides of these

spikes are provided with wedge faces α and thus as the spikes are driven into the tie, a clamping action is procured at the side edges of the rail which serves to anchor the rail to the tie and bed plate.

To provide a more positive anchoring means for the rail, portions of the bed plate opposite the passages 9 are provided with vertical passages 11 extending in the direction of the rail receiving recess 7 and having their inner sides disposed inwardly of the edges of the recess whereby to underlie the edges of a rail seated in the said recess. The outer sides of these passages are provided with intermediate outward extensions 12 for the reception of spikes 13 thus forming a general passage T-shaped in cross section. Disposed in the head portions of these passages are grip blocks 14 which have their upper portions extended inwardly to overlie the adjacent rail flange portions, and which are provided in their inner faces with recesses 15 receiving the edge portion of the rail, the inner faces of these recesses being toothed to have a biting engagement with the edge portions of the rail. The spikes 13 are also provided with wedge faces α at the upper portions of their outer sides and thus as they are driven through the portions 12 of the passages a wedge action is procured which clampingly engages the gripping blocks with the rail, the heads of these spikes overlying the grip blocks and the upper portion of these grip blocks being laterally turned to overlie the rail base flange, as heretofore stated, whereby the rail is firmly bound down upon the bed plate by the present structure, as well as efficiently anchored against horizontal movement. Each passage extension 12 is of less length than the width of the respective spike, and thus the spike extends into the main passage in its lateral clamping action. Also, the width of each gripping block 14 is less than the width of the respective passage 11 whereby the block may be inserted in the passage when the rail is positioned on the bed plate, and moved inwardly to engage the adjacent rail edge in its toothed recess 15.

From the foregoing it is seen that a comparatively simple device has been procured whereby the rail may be secured on the bed plate and the bed plate in turn secured on the tie and whereby the rail is efficiently anchored against creeping movement.

I claim:

A rail anchoring device comprising the combination of a tie, a rail bed plate disposed thereon and a rail on the plate, said plate being provided with passages having their inner edge portions extending under the rail, grip blocks insertible in the passages, and having their upper ends extended inwardly to overlie the rail base flange and provided at their inner sides with recesses receiving the rail base flange, teeth formed on the inner faces of said recesses and

headed wedge spikes extending through the passages into the tie and clampingly bearing against the blocks with the heads of said spikes engaging on said blocks to provide the securing means of the rail and bed plate to the tie. 15

In testimony that I claim the foregoing I have hereunto set my hand at Milwaukee, in the county of Milwaukee and State of Wisconsin. 20

DENNIS E. CROWLEY.
